SURGE FILTER FOR PULSATING GASES

Ralph L. Leadbetter, Wheaton, Ill., assignor, by
mesne assignments, to Burgess Battery Com-
pany, Chicago, Ill., a corporation of Delaware

Application August 31, 1938, Serial No. 227,654

16 Claims. (Cl. 181—54)

This invention relates to surge filters for flowing, pulsating gases, such as the exhaust gases of internal combustion engines, or, as the terms are loosely used, to improvements in mufflers and silencers for such pulsating gas systems.

This application is a continuation in part of my application Serial No. 130,283, filed March 11, 1937.

Although the invention is useful for the prevention of noise caused by pulsating gases generally, including, for example, the intake and delivery of air compressors, the most severe conditions are met in the prevention of noise caused by the exhaust of internal combustion engines and for this reason the invention will be illustrated and described as applied to this particular problem.

A large variety of constructions have heretofore been employed for the attenuation of noise resulting from the operation of internal combustion engines. Whether such mufflers employ baffles, resonating chambers, or equalizing or expansion chambers, an analysis of their operation discloses that their function depends entirely upon pressure fluctuations of the gas stream and thus their effectiveness depends upon their proximity to points of maximum pressure change in the exhaust system. Thus, a resonating chamber tuned to attenuate a particular frequency is inoperative when located at an (velocity) antinode of that particular sound wave which it is designed to attenuate. It will be seen from the following detailed description that the present invention constitutes a radical departure from mufflers and silencers heretofore known for the reason that it operates by virtue of the inertia imparted to the gases upon being ejected from the engine cylinder into the exhaust system. The invention operates as a velocity smoothing device and depends upon pressure only in the remote sense that the inertia of the exhaust gases depend upon a pressure in the engine cylinder at the time the exhaust valve is opened.

The fundamental distinction indicated in the preceding paragraph will become more apparent as the description of the invention proceeds.

The object of this invention is to prevent noise caused by flowing, pulsating gases by means of a device that may be located with equal effectiveness at any point in the conduit carrying the gas stream and to reduce back pressure and eliminate so-called "period" noises.

The essential element of a muffler embodying this invention is a receptacle or "snubber tube" into which the exhaust gases are projected at

high velocity from the exhaust ports of the engine. Part of the exhaust gases are conducted directly to the muffler outlet via a substantially unrestricted passageway without entering the snubber tube. Only that portion of each pulsation having sufficient inertia to cause it to jump a gap rather than deviate in its course to follow the line of least pressure resistance enters the snubber tube. The velocity of the gases entering the snubber tube is arrested and the gas pressure caused thereby dissipated through perforations in the walls of the snubber tube.

Several embodiments of the invention are illustrated in the accompanying drawings in which:

Fig. 1 is a longitudinal, sectional view of a device embodying the invention;

Fig. 2 is a longitudinal, sectional view of a modified form of the device the view being taken on line 2—2 of Fig. 4;

Fig. 3 is a longitudinal, sectional view of the device of Fig. 2 taken on line 3—3 of Fig. 4;

Fig. 4 is a transverse, sectional view of the device shown in Figs. 2 and 3, and

Fig. 5 is a longitudinal, sectional view of a further modification of the device.

The exhaust of an internal combustion engine consists largely of a series of rapidly traveling pulses of high pressure gas known to the art as "slugs." A high velocity peak, or slug, is formed each time an exhaust valve opens. Sound waves are thought to be caused by high velocity impact of these slugs with the atmosphere. These are the sharp cracks characteristic of the exhaust when not properly muffled. A low pitched rumble is maintained between explosions. These noises may be eliminated by dissipating the velocity peaks to smooth out the flow of the gases through the exhaust system before exhausting to the atmosphere at a relatively uniform velocity. In addition to these noises, period noises are caused at certain firing frequencies of the engine. These periods occur when the firing frequency substantially coincides with the natural resonant frequency of the exhaust system or a harmonic thereof, the timed recurrence of the pulsations tending to set the exhaust system in vibration. Periods may also occur when the exhaust slugs reinforce every second, or every third, etc., sound wave condensation without intervening neutralizing slugs. Resonance of the exhaust system depends largely upon reflection of the atmospheric impact into the system. The device of this invention, which will be referred to as a muffler for convenience, is effective in preventing

50
55

such impacts and thus in preventing both direct and period noises.

All of the mufflers are illustrated in their preferred forms, that is, contained within a single enveloping shell. The muffler of Fig. 1 employs a shell 10 which may be circular or elliptical in cross-section, the ends being closed by flanges 11 and 12 having inlet opening 13 and outlet opening 14, respectively. Inlet snout 15 is mounted 5 in inlet opening 13 and outlet snout 16 is mounted in outlet opening 14. These snouts are provided for convenience in mounting the muffler in the exhaust line. A snubber unit is arranged within the muffler. It consists of a perforated 10 snubber tube 17 mounted between partition 18 and end flange 12. Partition 18 is spaced from end flange 11 to form a by-pass chamber 19 and is provided with openings 20 and 21, the former opening being in register with opening 13 in 15 flange 11 and the latter opening being in non-alignment with opening 13. The mouth of snubber tube 17 is mounted on partition 18 at opening 20, the remote end of the snubber tube being closed by end flange 12. The ends of inlet snout 15 and/or snubber tube 17 may extend into by-pass chamber 19, but a gap α must be provided 20 between contiguous ends of these two members, this gap being not substantially less than one-fourth of the diameter of snout 15. In other 25 words, the cylindrical area forming the gap between the snout 15 and snubber tube 17 should not be substantially less than the cross-sectional area of the exhaust pipe of the engine. Substantially unrestricted flow of gases through snout 15 and by-pass chamber 19 to opening 21 is thus provided with the result that back pressure due to restriction within the muffler is practically nil. 30 Perforated conduit 22 is mounted on partition 18 at opening 21 and on end flange 12 at opening 40 14. Outlet snout 16 may be integral with conduit 22. Conduit 22 is perforated so that gases dissipated from snubber tube 17 through the 45 perforations therein may pass thereto. Space 23 operates as an expansion chamber to attenuate the high frequency sound waves and pulsations in conduit 22.

The engine exhaust gases enter the muffler through snout 15 and opening 13. The inertia 50 of the slug causes the gases forming the peak-velocity portion of the slug to jump the gap α and project into snubber tube 17 wherein the slug is cushioned and the velocity energy is transformed into static pressure which is dissipated through the perforations of the snubber tube. 55 The snubber tube must be of sufficient volume and sufficiently perforated to accommodate the velocity peak portion of the slug but must not be so extensively perforated that the slug will 60 be permitted to project through the walls of the snubber tube without undergoing the transformation described. The portion of the gases of the pulsation which do not have sufficient inertia to 65 jump the gap and enter the snubber tube follow the path of less resistance and flow through by-pass chamber 19 into conduit 22. A smoothing has been accomplished by the operation of the snubbing unit functioning as a surge filter and the gases are collected and discharged from the 70 muffler at outlet opening 14. The gases emerge from the muffler in a relatively smoothly flowing stream with greatly modified velocity peaks. Although the velocity of the gases leaving the muffler may still gradually rise and fall, there is 75 relatively little sound produced because there is

no impact of the moving gases with the atmosphere.

In a particular commercial muffler of the type described above and illustrated in Fig. 1 designed for an internal combustion automotive engine 5 of the V8 type having a maximum brake horse power of 85 at 3800 R. P. M. and a piston displacement of 221 cubic inches, the muffler is 18 inches long and 6 inches in diameter. Snubber tube 17 is 2 inches in diameter and tube 22 is also 10 2 inches in diameter. Partition 18 is spaced 1½ inches from the end flange 11 so that gap α is approximately 1½ inches. Tube 17 is perforated with $\frac{1}{8}$ inch holes spaced 2 inches apart on centers and tube 22 is perforated with similar holes 15 spaced 1 inch apart on centers.

The muffler illustrated in Figs. 2, 3 and 4 is similar to that above described with the addition of a third perforated collecting tube. Snubber tube 24 is mounted within shell 25 between partitions 26 and 27, the latter being spaced inwardly from end flanges 28 and 29 to form by-pass chamber 30 and expansion chamber 31 at the respective ends of the muffler. An inlet opening 32 and inlet snout 33 are provided to conduct the pulsating gases into the device and an outlet opening 34 and outlet snout 35 are provided to conduct the gases from the muffler. Conduit 36 is the counterpart of perforated conduit 22 in the muffler of Fig. 1 and connects by-pass chamber 30 with 25 expansion chamber 31, the latter being connected with the exhaust outlet. This conduit is illustrated as perforated but is not necessarily so since a perforated collecting tube 37 is provided to receive gases from the snubber tube 24. Collecting tube 37 is mounted between partitions 26 and 27 and opens into expansion chamber 31 but is closed at the other end by partition 26. This tube is perforated to a greater extent than conduit 36 thereby enabling gases in space 38 to enter the tube readily and pass into chamber 31. 40

Another species of the invention is shown in Fig. 5. This device embodies a pair of snubber units functioning independently of each other and illustrates a form which the snubber tubes 45 may take in order to provide a muffler which is relatively short in the direction of gas flow. It may be particularly useful for the prevention of noise from twin engines or a single engine having twin banks of cylinders. A casing 39 is provided 50 with a pair of inlet openings 40 and 41 having inlet snouts 42 and 43 mounted therein and an outlet opening 44 through which extends the outlet snout or tail pipe 45. A partition 46 is mounted transversely within the casing, being spaced from the inlet end thereof to form by-pass chamber 47. Perforated snubber tubes 48 and 49 having enlarged volumes, as shown, are mounted between the outlet end portion of the casing and partition 46, opening into by-pass chamber 47. Perforated 60 outlet conduit 50 connects by-pass chamber 47 with outlet opening 44 and may be integral with outlet snout 45.

The two modified forms of the invention operate as above described to attenuate the velocity peaks of the pulsating gases conducted through them. Any desired number of snubber units may be employed in a single device to operate independently of each other and any number of collecting tubes may be used. 70

The devices described herein which are only generally referred to as mufflers and have come to be known as snubbers, may be inserted at any point of the pulsating gas system. They may be used in appropriate sizes for the muffling of ex- 75

hausts of all types of engines, including large size Diesel engines, and also may be used in the prevention of noises at the intake and outlet of positive displacement blowers and air compressors. Since back pressures increase with the velocity of the gases traveling through a conduit, and since the snubber tube muffler substantially reduces peak velocities, the back pressures are accordingly greatly reduced by the device.

10 While several specific embodiments of the invention are shown, it is obvious that many modifications may be made without departing from the spirit thereof. The snubber tubes may be designed in various configurations for particular 15 embodiments and the gap between the inlet snout and the mouth of the snubber tube may be formed by a number of large openings in a continuous tube provided the totality of such openings is equivalent to a suitable gap. The lower limit 20 of the gap has been described above, but there is no critical upper limit.

I claim:

1. In a device of the character described including a shell, gas-velocity-peak snubbing means 25 within said shell and comprising means forming a chamber having an inlet opening and an outlet opening, conduit means arranged in said inlet opening and adapted to conduct gases into said chamber, a receptacle having apertured walls 30 and a mouth, said mouth of said receptacle being in direct communication with said chamber and in alignment with said conduit means whereby gases conducted into said chamber may project into said receptacle, and means for egress of 35 gases from said shell, said chamber outlet opening being in direct communication with said chamber inlet opening and in communication with said egress means.

2. A device in accordance with claim 1 characterized in that said receptacle is elongated in a direction in alignment with said conduit.

3. A device in accordance with claim 1 characterized in that the passageway through the conduit means, chamber, outlet opening and 45 egress means is substantially unrestricted to the flow of gases therethrough.

4. In a device of the character described including a shell having means for ingress of gases thereto and means for egress of gases therefrom, gas-velocity-peak snubbing means comprising 50 means forming a by-pass chamber having an inlet opening and an outlet opening, a conduit for conducting gases into said by-pass chamber arranged in said inlet opening and terminating 55 within said chamber, an apertured snubber tube having a mouth opening into said chamber in alignment with said conduit, the end of said conduit within said chamber being spaced from said snubber tube mouth to provide a gap through 60 which gases from said conduit may flow directly to said outlet opening.

5. A device in accordance with claim 4 in which the area of the gap between the conduit and the snubber tube mouth is not substantially 65 less than the transverse area of said conduit.

6. In a device of the character described comprising a shell having an inlet opening and an outlet opening in the respective ends thereof, a transverse partition within said shell spaced from 70 the inlet end thereof to form a by-pass chamber into which said inlet opening directly opens, an apertured snubber tube opening into said by-pass chamber, the mouth portion of said snubber tube being in alignment with said inlet opening and 75 spaced from the periphery thereof, and a per-

forated conduit connecting said by-pass chamber with said outlet opening.

7. The device of claim 6 in which the mouth portion of said snubber tube is spaced from the periphery of said inlet opening a distance not 5 substantially less than one-fourth the diameter of said inlet opening.

8. A muffler comprising a shell having an inlet opening and an outlet opening, a partition within 10 said shell forming a by-pass chamber adjacent said inlet opening which latter opens into said chamber, snubbing means comprising a tube in substantially axial alignment with said inlet opening, the walls of said tube being perforated, the inlet end of said tube opening into said by- 15 pass chamber and the opposite end being substantially closed said partition having a vent not in alignment with said inlet opening, a passageway substantially unrestricted to the flow of 20 gases therethrough extending from said inlet opening via said vent to said outlet opening, the degree of perforation of the walls of said tube being sufficient to allow a substantial part of the 25 gases entering said tube to pass through the perforations, the space surrounding said tube being in communication with said unrestricted passageway.

9. A muffler comprising a shell having an inlet opening and an outlet opening, a first partition within 30 said shell forming a by-pass chamber adjacent said inlet opening which latter opens into said by-pass chamber, a second partition forming an expansion chamber within said shell adjacent said outlet opening which latter opens into said expansion chamber, said first and second 35 partitions being spaced apart to form a space intermediate said chambers, a perforated tube in substantially axial alignment with said inlet opening and opening into said by-pass chamber the opposite end being closed, said tube extending 40 through said intermediate space to a point adjacent said expansion chamber, a tube in substantially axial alignment with said outlet opening and connecting said by-pass chamber and said expansion chamber, and a second perforated 45 tube opening into said expansion chamber and extending through said intermediate space to a point adjacent said by-pass chamber, the end of said second perforated tube adjacent said by-pass chamber being closed. 50

10. A muffler in accordance with claim 9 in which said tube connecting said by-pass chamber and said expansion chamber passes through said intermediate space and is perforated.

11. In a muffler having a cylindrical shell and 55 inlet-end and outlet-end closure plates, said said inlet-end closure plate having an inlet opening therein and said outlet-end closure plate having an outlet opening therein, a transverse partition within said shell forming a by-pass 60 chamber adjacent said inlet-end closure plate into which said inlet opening opens, a snubber tube arranged within said shell between said by-pass chamber and said outlet-end closure plate opening into said by-pass chamber, the mouth 65 portion of said snubber tube being in substantial alignment with said inlet opening and spaced from the contiguous peripheral portion of said inlet opening, said snubber tube having an enlarged portion at the end remote from the 70 mouth portion thereof, said partition having a vent not in alignment with said inlet opening, and means for connecting said vent with said outlet opening. 75

12. The muffler of claim 11 in which said means

- for connecting said vent with said outlet opening comprises a perforated conduit within said shell.
13. In a device of the character described, a shell having a plurality of inlet openings and an outlet opening, a partition within said shell forming a by-pass chamber into which said inlet openings open, conduit means associated with each of said inlet openings for conducting gases into said by-pass chamber, a perforated snubber tube opening into said by-pass chamber for each of said inlet openings, the mouth portion of each said snubber tube being in substantial alignment with its associated inlet opening and being spaced from the contiguous peripheral portion of said associated inlet opening, and a conduit within said shell connecting said by-pass chamber with said outlet opening.
14. The device of claim 13 in which the walls of said conduit connecting said by-pass chamber and said outlet opening are perforated.
15. The device of claim 13 in which said perforated snubber tubes are arranged within said shell and the walls of said conduit connecting said by-pass chamber and said outlet opening are perforated whereby communication is established between the interiors of said snubber tubes and said conduit.
16. The device of claim 13 in which each of said snubber tubes has a cylindrical portion adjacent the mouth thereof and a portion of enlarged cross-sectional area at the end remote from the mouth portion thereof.

RALPH L. LEADBETTER.
